UNITED STATES PATENT OFFICE.

ARNOLD H. HEUERMANN, OF TEUTOPOLIS, ILLINOIS.

LIQUID-DISPENSING APPARATUS.

Application filed May 18, 1923. Serial No. 639,820.

This invention relates to a dispensing apparatus and has for its principal object to provide a construction whereby regulating mechanism is employed capable of being adjusted so as to discharge the liquid from the tank in predetermined quantities.

Another important object of the invention is to provide a liquid dispensing apparatus of the above mentioned character, which is especially adapted for use in connection with concrete mixers or the like.

A still further object of the invention is to provide a liquid dispensing apparatus which is adapted for use with concrete mixing machines wherein it is desirous of measuring the several ingredients used in preparing the concrete.

Another important object of the invention is to provide a liquid dispensing apparatus which is simple in construction, inexpensive, strong, durable and further well adapted for the purposes for which it is designated.

Other objects and advantages of this invention will become apparent during the course of the following description.

In the accompanying drawings forming a part of this specification and in which like numerals designate like parts throughout the same:—

Figure 1 is a central vertical section through a tank embodying my improvement.

Figure 2 is a vertical section as seen on the line 2—2 of Figure 1, looking in the direction of the arrows.

Figure 3 is a section taken just above the member 21, with parts being broken away.

Figure 4 is a side elevation of the float valve mechanism, and

Figure 5 is a detail section taken just above the valve in the inlet pipe.

In the drawings wherein for the purpose of illustration is shown the preferred embodiment of my invention, the numeral 1 indicates the tank, which may be of any desirable form but is preferably of the shape illustrated in the drawings. The top of the tank 1 is provided with an inlet opening 2 adjacent one end thereof and extending upwardly from the top of the tank 1 and fitting within said inlet opening 2 is the inlet pipe 3. This inlet pipe 3 has the lower end thereof threaded, as shown at 4, to engage the threads of the inlet opening 2. The inlet pipe 3 is of a substantial length and is provided at its upper end with the valve 5, the

valve 5 being of the usual construction. It is not thought necessary to go into detail as to the construction of the valve. The upper end of the inlet pipe 3, it is to be understood is to be connected to a suitable source of water supply for the purposes hereinafter to be more fully described.

The tank 1 is also provided with an outlet opening 6 in the bottom of the tank 65 adapted for the attachment of the downwardly extending outlet or discharge pipe 7. The outlet pipe 7 is also provided with a valve 8 similar to the valve 5 in the inlet pipe 3 and it is to be understood that the valve 5 is in an open position in the inlet pipe 3 when the valve 7 is in a closed position in the discharge or outlet pipe 7. The lower end of the outlet pipe 7 is provided with a suitable nipple 9 whereby the same 75 may be connected to the concrete mixer, not shown, for the purposes of supplying the water from the tank 1 to the concrete mixing machine.

The valves 5 and 8 respectively are provided with the outwardly extending levers 10 and 11 respectively and the free ends of these levers 10 and 11 are fastened or connected by any suitable fastening means to the elongated actuating rod 12. The rod 12 85 has at its lower end and pivotally connected thereto the handle 13 which is pivotally supported at 14 upon any suitable support 15. The purpose of this construction is to enable the operation of the valves 5 and 8 90 respectively to be closed and opened simultaneously by the operation of the handle 13 and the actuating rod 12 which is connected to the levers 10 and 11.

The tank 1 is provided with an enlarged 95 opening 16 in the top thereof and a suitable cover 17 is provided therefor. This opening 16 is to enable a person to have access to the interior of the tank 1 whenever necessary and also for the purposes of assembling 100 various parts which are contained within the receptacle or tank 1.

A tube 18 which is of a diameter slightly less than the diameter of the inlet pipe 3 is enclosed within the tank 1 and has its upper 105 end slidably received in the inlet pipe 3 as shown more clearly in Fig. 1 of the drawings. The upper end of the tube 18 is furthermore provided with the packings 19 to insure a proper fit between the tube 18 110 and the inlet pipe 3. The tube 18 is provided with the angular extension 20 and this

extension 20 is provided with the enlarged head 21. The enlarged head 21 is provided with an opening 22 and this opening 22 is internally threaded. Receivable in the threaded opening 22 is the short piece of pipe 23 which is adapted to extend downwardly in the tank 1 as more clearly shown in Fig. 1 of the drawings. A valve 24 is pivotally supported in the enlarged head 21 adjacent the threaded opening 22 and is adapted to close the opening 22 as will be more fully described.

The pintle or shaft 25 upon which the valve 24 is carried extends transversely across the enlarged head and one end thereof extends beyond the outer face of the enlarged head 21 and carried on the outer end of this pintle 25 is the rack segment 26. This rack segment 26 is adapted to mesh with the larger rack segment 27 which is carried by the shaft 28 and transversely across the extension 23 and also keyed to the shaft 28 and extending in the direction opposite to the segmental gears or racks 26 and 27 is the arm 29 and this arm 29 carries at its outer end the float 30. The float may be constructed of sheet metal or the like and I do not wish to limit myself to the particular construction or use of the particular kind of float as any kind of float may be used for the purposes necessary in carrying out the essential features of my invention.

The enlarged head 21 may also be provided with an opening and a suitable covering 31 therefor in the top of the enlarged head for the purpose of enabling a person to have ready access to the interior of the enlarged head whenever necessary to remove the valve 24.

A suitable collar 32 is provided on the tube 18 adjacent the lower end thereof and the purpose of this collar 32 is to provide a means whereby the tube 18, the enlarged head 21 carried thereby and the float mechanism heretofore described may be moved upwardly or downwardly, as the case necessitates and as will be more fully described.

Extending through a suitable opening 33 provided in the top of the tank 1 and adjacent the inlet pipe 3 is the rack bar 34 and the lower end of the rack bar 34 is provided with a ringlike extension 35 for engagement with the underface of the collar 32 carried by the tube 18 for the purposes of raising or lowering the tube 18 and the float mechanism associated therewith. Extending through a suitable support 36 mounted upon the top of the tank 1 and in close proximity to the opening 33 is the shaft 37. This shaft has at one end provided a pinion 38 which is adapted to mesh with the rack bar 34 for the purposes of actuating the same and a suitable handle 39 is provided or carried upon the outer end of the shaft 37 for actuating the pinion 38. A pawl 40 is piv-

otally supported in the bracket 41 on the tank 1 and this pawl 40 is adapted to engage the pinion 38 for holding the same and the rack bar 34 in its adjusted position.

In use, the handle 39 is actuated to raise or lower the tube 18 and the float mechanism carried thereby whereby the float 30 is brought to a predetermined height within the tank 1 so as to permit a certain quantity of water or other liquid to be admitted or supplied into the tank 1 whereby the same may be discharged therefrom into the concrete mixer. It is to be understood that when the handle 39 is rotated the pinion 38 will mesh with the rack bar 34 and raise the tube 18 causing the upper end to be moved vertically in the inlet pipe 3 and at the same time raise the float mechanism. When the float 30 has been raised to the predetermined height by the means heretofore described, the pawl 40 will hold the rack bar in its adjusted position and will prevent the accidental downward movement of the tube 18 and the float mechanism carried thereby. Normally the float 30 through the medium of the segmental gears 26 and 27 cause the valve 24 in the enlarged head 21 to remain open. With the valve 24 in its unseated position and by having the inlet valve 5 open and the discharge valve 8 closed, the water admitted through the inlet pipe 3 and the tube 18 will flow through the enlarged head 21, through the opening 22 provided therein and through the extension 23 being discharged into the tank 1. As the water reaches the predetermined height at which the float is adapted to operate, the float 30 will cause the segmental gear 27 to actuate the segmental gear 26 whereby the valve 24 will be brought into engagement with the opening 22 closing the opening and thereby shutting off the supply of water in the tank 1. For the purposes of ascertaining whether or not the liquid has reached the predetermined height, the tank may be provided with a suitable sight gauge in one side thereof.

Upon the water reaching the predetermined height in the tank 1, the handle 39 is actuated in the manner heretofore described whereby the valve 5 is caused to be closed and the valve 8 simultaneously opened thereby permitting the water in the tank 1 to be discharged through the outlet pipe 7 and into the concrete mixing machine wherever it is used. At the same time the float 30 will be returned to its normal position, opening the valve 24 and causing the water which is collected in the inlet pipe 3 and the tube 18 to be discharged into the tank 1 where it is furthermore discharged through the outlet pipe 7.

It will be seen from the foregoing description that a liquid dispensing apparatus has been provided wherein a certain

quantity of liquid may be measured into a tank and the same dispensed therefrom in a simple and efficient manner. Furthermore the manner in which the liquid is measured enables the tank to be used for various purposes and is not alone restricted to the use of a concrete mixing machine.

From the foregoing description of the construction of my improved apparatus, it will be seen that I have provided a simple, inexpensive and efficient means for carrying out the objects of the invention and while I have particularly described the elements best adapted to perform the functions set forth, it is obvious that various changes in form, proportion and in the minor details of construction may be resorted to, without departing from the spirit or sacrificing any of the principles of the invention.

What I claim as new and desire to secure by Letters Patent is:—

1. A liquid dispensing apparatus comprising a tank, an inlet pipe extending upwardly therefrom, a discharge pipe extending from the bottom of said tank, a valve in each of said pipes, the valve in said inlet pipe being open when the valve in said discharge pipe is closed, a tube in said tank having its upper end slidably receivable in said inlet pipe, a float mechanism associated with said tube, and adapted to control the liquid supply through said inlet pipe and said tube, and means for manually raising and lowering said tube for adjusting said float mechanism to a predetermined height.

2. A liquid dispensing apparatus comprising a tank, an inlet pipe extending upwardly therefrom, a discharge pipe extending from the bottom of said tank, a valve in each of said pipes, the valve in said inlet pipe being open when the valve in said discharge pipe is closed, a tube in said tank having its upper end slidably received in said inlet pipe, an enlarged head carried by the lower end of said tube, a float controlled valve carried by said enlarged head, means externally arranged on said tank and cooperating with said tube for manually raising and lowering the latter and simultaneously adjusting the height of said float valve mechanism within the tank, and means for operating said inlet and outlet valves simultaneously.

3. A liquid dispensing apparatus comprising a tank, an inlet pipe extending upwardly therefrom, a discharge pipe extending from the bottom of said tank, a valve in each of said pipes, the valve in said inlet pipe being open when the valve in said discharge pipe is closed, a tube in said tank and having its upper end slidably received in said inlet pipe, an enlarged head threaded into engagement with the lower end of said tube, a float controlled valve carried by said enlarged head, means externally ar-

ranged on said tank and cooperating with said tube for manually raising and lowering the latter and simultaneously adjusting the height of said float valve mechanism within the tank, and means for operating said inlet and outlet valves simultaneously.

4. A liquid dispensing apparatus comprising a tank, an inlet pipe extending upwardly therefrom, a discharge pipe extending from the bottom of said tank, a valve in each of said pipes, means for actuating said valves so that the valve in the inlet pipe will be open when the valve in the discharge pipe is closed, a tube disposed in said tank and having its upper portion slidably mounted in said inlet pipe, an enlarged head threaded into engagement with the lower end of said tube, a float-controlled valve mounted in said head, a vertical rack member removably secured to the lower end of said tube and projecting through an opening in the top of said tank, a laterally projecting shaft rotatably supported on the top of said tank, a pinion mounted on one end of said shaft meshing with the teeth of said rack, and a handle member carried on the outer end of said shaft for rotating the latter and correspondingly raising and lowering said tube to adjust the height of said float controlled valve within the tank, as and for the purposes described.

5. A liquid dispensing apparatus comprising a tank, an inlet pipe extending upwardly therefrom, a discharge pipe extending from the bottom of said tank, a valve in each of said pipes, means for actuating said valves so that the valve in the inlet pipe will be open when the valve in the discharge pipe is closed, a tube disposed in said tank and having its upper portion slidably mounted in said inlet pipe, an enlarged hollow head member having a tubular extension formed thereon threaded into engagement with the lower end of said tube, said head member being provided with an upper threaded opening, a closure engaged with the threaded opening of said head member, said head member being also provided in the side wall adjacent its lower end with a threaded opening, a short pipe section having one end threaded into engagement with the last mentioned threaded opening in the head member and extending downwardly and outwardly with respect to the latter, a pivoted valve member supported within the head member to form a closure for the inner end of said short pipe section, a float member fulcrumed on the outer end of said short pipe section and having connection at its inner end with said valve to actuate the latter, and means for raising and lowering said tube within the tank, as and for the purposes described.

In testimony whereof I affix my signature.
ARNOLD H. HEUERMANN.
